UNITED STATES PATENT OFFICE.

FRANK. R. PEACOCK, OF LE MARS, IOWA.

WELL-DRILLING MACHINE.

SPECIFICATION forming part of Letters Patent No. 416,375, dated December 3, 1889.

Application filed October 6, 1888. Serial No. 287,356. (No model.)

To all whom it may concern:

Be it known that I, FRANK. R. PEACOCK, a citizen of the United States, residing at Le Mars, in the county of Plymouth and State of Iowa, have invented a new and useful Improvement in Well-Drilling Machines, of which the following is a specification.

My invention relates to an improvement in well-drilling machines; and it consists in the peculiar construction and combination of devices that will be more fully set forth herein-after, and particularly pointed out in the claims.

The object of my invention is to provide a machine which is adapted to operate any kind of tools now commonly employed for drilling a well, and by means of which the drill may be operated either by the drill-rope or cable-rope and raised or lowered into or out of the well, and by means of which the sand-pump may be also operated.

In the drawings, Figure 1 is a side elevation of a well-boring machine embodying my improvements. Fig. 2 is a top plan view of the same, showing the devices in adjustment for operating the drill-rope drum. Fig. 3 is a similar view showing the same arranged in position for operating the cable-drum. Fig. 4 is a similar view showing the same arranged for operating the sand-pump-rope drum. Fig. 5 is a vertical longitudinal sectional view, taken on the line *x x* of Fig. 2, and looking in the direction of the arrow *a* in the said figure. Fig. 6 is a similar view, taken on the line *y y* of Fig. 2, and looking in the direction indicated by the arrow *b* in the said figure. Fig. 7 is a vertical transverse sectional view taken on the line *w w* of Fig. 3. Fig. 8 is a similar view taken on the line *z z* of the said figure. Fig. 9 is a detail perspective view of a modified form of drill-rope drum and attachments therefor, whereby the said drum is adapted to be operated by horse-power. Fig. 10 is a sectional view of the same.

A represents a rectangular frame, which comprises the side beams B, the cross-beams C D, connecting opposite ends thereof, the bar E, connecting the upper sides of the side beams and arranged in proximity to the beam C, and the transverse beam F, connecting the side beams B at the lower sides thereof and arranged at a suitable distance from the beam

C. This frame is adapted to be supported on a suitable truck or wagon (not shown) in the usual manner, or it may be supported on suitable sills, (not shown,) according to the size and weight of the machine. 55

G represents the derrick, which comprises the pair of legs H, connected by the cross-bars I, and the pair of legs K, connected by a cross-bar L, at a suitable distance from their upper ends. The upper ends of the said pairs of legs are hinged together by a bolt M. On the central portion of this bolt is journaled a pulley N. 60

O represents a block, which is suspended from the bolt M by means of links P, and is provided with pulleys R. The lower ends of legs H are pivoted or hinged to the inner end of the frame A, on opposite sides thereof, by 70 means of bolts U.

V represents a shaft, which is journaled in bearings W on the sides of the frame, at a suitable distance from the outer end thereof. On one end of the said shaft is secured a band-pulley W and a driving-pulley X. 75

Y represents a cable-drum, which is loosely mounted on the said shaft and has at one end a friction-hub Z and a clutch-section A'.

B' represents a clutch, which is feathered 80 on the said shaft and is adapted to engage and disengage the clutch-section of the cable-drum so as to lock the latter to the shaft or adapt it to rotate independently thereof. A spring C' bears against the outer side of the 85 said clutch, and is adapted to keep the same normally in engagement with the clutch A'.

D' represents a lever, which is fulcrumed in a support E', is adapted to move vertically on its fulcrum-bolt F', and has its outer end provided with a depending lip or plate G', which is adapted to engage a notched detent H' on one corner of the frame. The inner end of the said lever is connected to a ring or collar that is swiveled on the clutch B', and the detent-plate may be engaged by the said lever so as to lock the same in position with the clutch either in or out of engagement with the cable-drum. A spring I' bears on the lever D' and serves to keep the latter normally 95 in engagement with the detent-plate.

K' represents a lever, which is fulcrumed in a bearing or support on the cross-bar E, and is provided with a friction-strap L', which

passes around the friction-hub Z of the cable-drum. By depressing the said lever the friction-strap is compressed on the said hub, so as to lock the cable-drum against rotation, 5 and by elevating the said lever the friction-strap is loosened on the drum. A hook M' depends from the said lever, and a chain N' is secured to the outer end of the frame and adapted to be engaged by said hook at any 10 point of its length, the function of the said chain being to secure the lever in position when the latter is lowered to apply the brake-strap L'.

O' represents a shaft, which is arranged at 15 a suitable distance from the shaft V and parallel therewith, and is journaled in bearings P' on the upper side of the frame. Loosely mounted on the said shaft is a sand-pump-rope drum R', which has at one end a 20 clutch-section S', and is provided at its opposite end with a friction-hub T'. To the opposite end of the shaft is secured a spur-wheel U'.

V' represents a sleeve, which is feathered 25 on the shaft O', has at one end a clutch-section W', which is adapted to engage the clutch-section S' of the sand-pump drum, and at the opposite end of the said sleeve is a cam X', which is equal to one-third the circumference 30 of the sleeve. From the center of the sleeve projects an annular flange Y', which has an annular groove Z' on its outer side.

A² represents a feed-wheel, which is loosely mounted on the shaft O' and bears against 35 one side of the frame. Said feed-wheel has openings B² near its periphery at suitable regular distances apart, and on the inner side of the feed-wheel is formed a cam C², which is adapted to be engaged by the cam X', as 40 will be hereinafter stated. The feed-wheel is prevented from moving laterally on the shaft O' by a guide D², which engages said feed-wheel.

E² represents a lever, which is provided at 45 one end with a pin F², that is adapted to engage one of the openings of the feed-wheel and thereby lock the latter against rotation. A spring G² bears against the opposite end of the lever and serves to keep the said pin 50 normally in engagement with the feed-wheel.

H² represents a shaft, which is journaled in bearings in the side of the frame at a suitable distance below the shaft O'. Said shaft H² has at one end a spur-wheel I², which engages the wheel U', and the said shaft is further provided with a sprocket-wheel K².

L² represents a shaft, which is journaled in bearings on the sides of the frame A near the inner end thereof. On this shaft is loosely 60 mounted a drill-rope drum M², which has a hub or projection provided with ratchet-teeth N² at its outer end. At the inner end of said drill-rope drum is a friction-hub O² and a clutch-section P².

65 R² represents a lever, which is fulcrumed in a support S² on one side of the frame, and has attached to it the ends of a friction-strap

T², which strap engages the friction-hub T' of the sand-pump-rope drum. The outer end 70 of the lever R² has a hook U², which is adapted to be engaged by a chain V², and thereby secure the said lever when the same is depressed and apply the friction strap or brake to the sand-pump-rope drum.

W² represents a clutch, which is feathered 75 on the shaft L², and is adapted to engage the clutch-section P² of the drill-rope drum. The said clutch has the usual annular groove, which is engaged by one end of a lever X², which lever is fulcrumed in the end of an 80 arm or bracket Y², that projects inward from one side of the frame. The opposite end of the said lever has a head Z², which is provided with a central opening, of suitable size, to clear the clutch-sleeve V', and said head is 85 further provided with anti-friction rollers D³, which are arranged in the same opening and adapted to bear against the inner side of the flange Y'.

B³ represents a catch-arm, which is pivoted 90 to the outer side of the head Z², for the purpose to be presently stated.

C³ represents a lever, which is fulcrumed to the arm or bracket Y², and is arranged on the outer side of the lever X². The inner end of 95 the said lever C³ is forked or bifurcated and extended over the clutch-sleeve V', and to the arms or forks of said lever are journaled anti-friction rollers D³, which are adapted to engage the outer side of flange Y'. The outer 100 end of the said lever extends through a slot or opening E³ in the inner end of frame A, and passes through a slotted guide-plate F³, which is secured on the said inner end of the frame. Said slotted guide-plate is provided with openings 1 2, arranged at a suitable 105 distance apart, the said openings communicating with and intersecting the slot in the said plate. Pins 3 and 4 are adapted to be inserted in both of the said openings, so as 110 to secure the lever in any desired position, as will be hereinafter more fully stated.

G³ represents a lever, which is fulcrumed on the support at the inner end of the frame, and attached to the said lever are the ends of a 115 friction or brake strap H³, which engages the friction-hub O² of the drill-rope drum.

I³ represents a dog or detent, which is also fulcrumed in a bearing on the inner end of the frame, and is adapted to engage the 120 ratchet-teeth of the drill-rope drum to prevent the latter from rotating in a retrograde direction on the shaft L².

K³ represents a sprocket-wheel, which is loosely mounted on the shaft L² and is of less 125 diameter than the sprocket-wheel K², and is connected to said sprocket-wheel by means of a sprocket-chain L³.

On the inner side of sprocket-wheel K³ is a clutch-section M³, and on the outer side 130 thereof is an extension or hub which is provided with an annular groove.

N³ represents a lever, which is fulcrumed and vertically movable on a support O³,

and has its inner end bifurcated or forked and engaging the grooved extension of the loosely-mounted sprocket-wheel K^3 . The outer end of the said lever is adapted to engage either of the recesses or notches P^3 R^3 , of a detent-plate S^3 , which is secured on one of the inner corners of the frame.

T^3 represents a clutch, which is keyed fast on the shaft L^2 , and is adapted to engage the clutch-section of the sprocket-wheel K^3 . A spring U^3 bears between the clutch W^2 and clutch T^3 , and keeps the former normally in engagement with the clutch-section of the drill-rope drum.

15 To one end of the shaft L^2 is secured a drum or pulley V^3 , and to the opposite end thereof is secured a wheel W^3 , which is of greater diameter than the wheel W and is connected thereto by means of an endless belt X^3 .

20 Y^3 represents a belt-tightening lever, which is fulcrumed on one side of the frame and has at its inner end an anti-friction roller Z^3 , which is adapted to engage the lower side of the belt X^3 and tighten the same on the wheels 25 W and W^3 . The outer end of the said lever is adapted to engage a rack-bar A^4 , secured at one of the outer corners of the frame, whereby the said belt-tightening lever may be maintained at any desired adjustment.

30 To the drum Y is attached a cable a , which passes over one of the pulleys R . To the drum R' is attached a sand-pump rope b , which passes over another of the pulleys R , and to the drum M^2 is attached a drill-rope c , 35 which passes over the last pulley R .

The operation of my invention is as follows: The frame is mounted alongside the proposed well and the derrick mounted over the same, so that the block at its upper end is directly 40 over the well. In order to drill, the usual tools are attached to the pendent end of the drill-rope, the belt-tightener is applied to the belt, the lever D^3 is moved to throw its clutch out of engagement with the drum Y , so that 45 the latter is loose on its shaft, the brake is applied to the said drum to prevent it from rotating, the brake is applied to the drum R' , the brake is released from the drill-rope drum, the dog or detent I^3 is released from the 50 ratchet-teeth of said drill-rope drum, the lever N^3 is operated to throw the clutch-section of sprocket-wheel K^3 into engagement with the clutch T^3 , and the lever C^3 is disengaged from the guide-plate F^3 by removing the pin 55 3 . This arrangement of the machine is illustrated in Fig. 2. Rotary motion is then applied to the driving-shaft V from a suitable motor, (not shown,) and the said shaft is caused to rotate. The wheels W W^3 and end- 60 less belt X^3 communicate this rotary motion to the shaft L^2 and drive the latter at a somewhat decreased rate of speed, and the sprocket-wheels and sprocket-chain rotate the shaft H^2 at a still further reduced rate of speed by 65 reason of the wheel K^2 being larger than the wheel K^3 . The wheels I^2 and U' communicate rotary motion to the shaft O' , and con-

sequently to the sleeve V' , which is feathered on the said shaft. The clutch W^2 is normally in engagement with the clutch-section of the 70 drill-rope drum, and thereby the rotary motion of the shaft L^2 is communicated to said drum and the latter is caused to coil the drill-rope, so as to raise the drill. This rotary movement of the drill-rope drum continues 75 while the clutch-sleeve V' is making a partial or two-thirds revolution, when the cam X' of said sleeve comes in engagement with the cam C^2 on the feed-wheel, and as the said clutch-sleeve completes its rotation the 80 said cams X' and C^2 move the said sleeve longitudinally on the shaft O' toward the sand-pump-rope drum, and the friction-rollers A^3 of the lever X^2 , by engaging the flange Y' of the clamp-sleeve, cause the said 85 lever to turn on its fulcrum, withdraw the clutch W^2 against the tension of the spring U^3 from the clutch-section on the drill-rope drum, and thereby momentarily release the latter, and consequently enable the drill to descend in the well by its own weight and cause the drill-rope to partly uncoil on the drill-rope drum and thereby rotate the latter in a retrograde direction. As the drilling proceeds the 90 drill-rope is gradually paid out from the drill-rope drum, this being accomplished by the operator, who releases the pin F^2 from the feed-wheel, turns the latter in the direction indicated by the arrow, and re-engages the same in another opening in the feed wheel. To take 95 up the slack rope the foregoing operation is reversed.

The operation of the machine is the same when employed for driving a casing down into the well, the only difference being that the 100 driving-aul is substituted for the drilling-tools.

In order to draw the drilling-tool from the well, a spring U^3 holds the clutch W^2 in engagement with the clutch-section of the drill-rope drum, and the lever N^3 is engaged with the notch P^3 of the plate S^3 , so as to release the wheel K^3 from the clutch T^3 , and thereby adapt the shaft L^2 to rotate independently of said sprocket-wheel. The operator then grasps the 110 lever I^3 and causes the same to engage the teeth of the drill-rope drum, and motion is imparted to the shaft V as before, and transmitted from said shaft V to the shaft L^2 , and the clutch W^2 being in engagement with the 115 clutch-section of the drill-rope drum the latter is caused to wind up the drill-rope and to consequently elevate the drill. When the latter 120 clears the well, the operator applies the break H^3 to the friction-hub of the drill-rope drum 125 and moves the lever X^2 to cause the clutch W^2 to disengage said drill-rope drum, and thereby cause the latter to rotate independently of its shaft, when the drill may be lowered to the ground, as will be readily understood.

130 While the machine is used for drilling, the length of the drop of the drill may be increased by putting a smaller wheel I^2 on the shaft H^2 and a correspondingly larger wheel U'

- on the shaft O'. This causes the said shaft O' to rotate at a still further decreased rate of speed, and consequently permit the drill-rope drum to wind up more rope and lift the tool 5 higher than before. To shorten the stroke of the drill-tool, the arrangement before described is reversed, the larger wheel being secured on shaft H² and the smaller wheel on the shaft O'.
- 10 In order to drill with the cable, the drilling-tool is attached to the cable and the latter clamped to the drill-rope by a suitable rope-clamp, (not shown,) and the machine is adjusted, as before described, for drilling purposes, care being taken to let out plenty of slack rope from the cable-drum. The machine then operates as before described, the drill-rope and drum serving to alternately raise and drop the tool, as before.
- 15 20 In the event it should become desirable for any reason to hoist the drilling-tool from the well, this may be accomplished by releasing the rope-clamp, disengaging clutch W², and locking lever C³ between openings 1 2 and pins 3 4 on each side of said lever C³, by releasing the brake L' from the cable-drum, and causing the clutch B' to engage the clutch-section of the cable-drum, and hence causing the rotation of the shaft V to be communicated to 25 the cable-drum, so that the cable will be coiled on the latter. When the drilling-tool has been hoisted from the well and it is desired to lower the same from the derrick onto the ground, the cable-drum is thrown out of engagement 30 with the shaft V by operating the lever D', and the operator grasps the brake-lever K' and applies sufficient friction to the friction-hub of the cable-drum to cause the latter to rotate slowly in a reverse direction, and there- 35 40 by partly uncoil the cable and lower the tool.
- In order to operate the sand-pump, the cable-drum is disconnected from the shaft V by detaching the clutch B' from the said cable-drum. The brake L' is applied to the latter 45 to prevent it from rotating. The brake H² is applied to the drill-rope drum. The lever C³ is locked to the lever X² by means of the catch-arm D³. The brake R² is disengaged from the drum R', and the lever C³ is secured 50 in one end of the guide-plate by inserting the pin 3 in the opening 2 of said guide-plate and causing said pin to bear against the inner side of said lever C³. This causes the friction-rollers on the inner end of lever C³ to bear 55 against the outer side of the flange Y', and thereby force the clutch-sleeve V' into engagement with the clutch-section of the drum R'. By inserting the pin 4 in the opening 1 it prevents clutch W² going into engagement 60 with clutch-section of the drum M² when clutch-section W' is disengaged from clutch-section S'. The lever N³ is adjusted to move the sprocket-wheel into engagement with clutch T³, and thereby the rotation of shaft 65 L² is communicated to the shaft H² by the sprocket wheels and chain, and from said shaft H² to the shaft O' by the gears I² and U', and

the sand-pump being attached to the rope b, and the sand-pump rope being in engagement and rotating with the shaft O', the said rope b will be coiled on the said drum, and consequently the sand-pump will be raised. In order to lower the sand-pump, the lever C³ is shifted to throw the clutch-section W' out of engagement with the clutch S', and consequently the sand-pump drum is adapted to turn loosely on its shaft O' and the weight of the sand-pump causes the same to descend. The speed with which the sand-pump descends may be controlled by the brake R², as will be readily understood.

The operation of the machine may be at any time checked instantly by moving the belt-tightener in such manner as to cause its anti-friction roller to slacken the endless belt 85 X³, and hence permit the shaft V to rotate without transmitting motion to the shaft L².

When using gas-pipe tools, the hollow driving-block commonly employed is slipped over the drill-rod, the bottom of said block resting 90 normally on the top of the casing. A rope d is attached to the said block, passed over the said sheave or pulley at the upper end of the derrick, and is coiled once or twice around the drum V³, one end of the said rope being 95 extended from the said drum. When the shaft L² is rotated, the drive-block may be raised at any time by pulling on the loose end of the rope d to cause the latter to tighten on drum V³ with a degree of friction sufficient 100 to cause the said drum to draw upon the said rope, and said hollow block may be lowered by slackening said rope on said drum so that it slips idly thereon. This drum V³ may also be employed for hoisting heavy casing into 105 the derrick, so that the sections thereof may be screwed together.

In Figs. 9 and 10 I illustrate a modified form of my invention, adapted to be operated by horse-power, in which the drill-rope drum 110 M² is provided at one end with a tappet pin or stud m², and the clutch W² has a tappet-arm w² projecting from one side and provided with a buffer w³, adapted to contact with the tappet pin or stud. By this arrangement 115 when the machine is drilling the shaft L² causes the drill-rope drum to rotate there-with as long as the clutch W² is in engagement with said drum, and when said clutch is shifted out of engagement with the drum by 120 the lever X² to release the drum from its shaft and permit it to partly rotate thereon in a reverse direction and let the drill-tool drop, as before stated, the tappet-arm of said clutch is still in the path of the tappet pin or stud of 125 the drill-rope drum, and hence the latter cannot make more than a single revolution in a reverse direction, no matter what may be the speed of the machine.

Having thus described my invention, I 130 claim—

1. The combination, in a well-drilling machine, of the shaft L², means to rotate the same, the drill-rope drum loose on said shaft

and having a clutch thereon, the spring-pressed clutch W^2 , feathered on the shaft and adapted to normally engage said clutch, the lever X^2 , attached to clutch W^2 , the cam C^2 , the cam-sleeve V' , having cam X' to engage said cam C^2 , said sleeve being connected to the lever, and sprocket chains and wheels, substantially as set forth, between the shaft L^2 and the cam-sleeve, to rotate the latter, whereby the drill-rope drum will be alternately rotated and released, for the purpose set forth, substantially as described.

2. The combination, in a well-drilling machine, of the shaft L^2 , the drum loose thereon and provided with a clutch, the spring-pressed clutch W^2 , feathered on said shaft and normally engaging said clutch, the lever X^2 , attached to said clutch, the shaft O' , the sleeve V' , feathered on said shaft, connected to lever X^2 , and having cam X' , the relatively stationary cam C^2 , adapted to engage cam X' and connections, substantially as described, between the shafts L^2 and O' , for the purpose set forth.

25 3. The combination of the shaft L^2 , the drill-rope drum loose thereon and provided with a clutch, the spring-pressed clutch W^2 , normally engaging said clutch, the lever X^2 , connected to said clutch, the shaft O' , the sleeve V' , feathered thereon and having cam X' , said sleeve being connected to lever X^2 , the feed-wheel loose on shaft O' and having cam C^2 , the detent to lock the feed-wheel, and connections, substantially as described, between the shafts L^2 and O' , whereby the cam-sleeve is rotated, substantially as described.

35 4. The combination of the shaft L^2 , the drill-rope drum mounted loose thereon and

provided with a clutch, the spring-pressed clutch W^2 , feathered on said shaft, the lever X^2 , connected to said clutch W^2 , the shaft O' , the cam-sleeve feathered thereon and connected to the lever, the relatively-fixed cam C^2 , adapted to engage the cam-sleeve for the purpose set forth, the shaft H^2 , the sprocket-wheels and chain connecting the same to shaft L^2 , and gear-wheels connecting shaft H^2 to shaft O' , for the purpose set forth, substantially as described.

5. The combination of the shaft L^2 , the drill-rope drum loose thereon and provided with a clutch, the spring-pressed clutch W^2 , feathered on the shaft to engage said clutch, the clutch T^3 , fastened to said shaft, the sprocket-wheel K^3 , loose on said shaft and having the clutch to engage clutch T^3 , the lever N^3 to operate said wheel, the shaft O' , the drum R' , loose thereon, the clutch-sleeve V' , feathered on said shaft and having cam X' , the relatively stationary cam C^2 , to engage cam X' , the shaft H^2 , having the sprocket-wheel K^2 , the chain connecting the latter to wheel K^3 , the lever X^2 , attached to clutch W^2 , and sleeve Z , the lever C^3 , the device to lock the said levers together, the latter being each adapted to move sleeve V' in one direction, and the gears connecting shafts H^2 and O' , substantially as described.

In testimony that I claim the foregoing as my own I have hereto affixed my signature in presence of two witnesses.

FRANK. R. PEACOCK.
